UNITED STATES PATENT OFFICE.

HERBERT E. ENSLIN, OF MALDEN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

BUTTONING-MACHINE.

1,273,444.

Specification of Letters Patent. Patented July 23, 1918.

Application filed August 22, 1917. Serial No. 187,659.

To all whom it may concern:

Be it known that I, HERBERT E. ENSLIN, a citizen of the United States, residing at Malden, in the county of Middlesex and 5 State of Massachusetts, have invented certain Improvements in Buttoning-Machines, of which the following description, in connection with the accompanying drawings, is a specification, like reference characters on 10 the drawings indicating like parts in the several figures.

This invention relates to buttoning machines, and an object of the invention is to improve the efficiency of machines of this 15 class and render them more readily adaptable to the conditions encountered in operating upon a wide variety of work. More particularly, an important object is to provide improvements especially adapted to be 20 incorporated in machines of the general type illustrated in United States Letters Patent No. 1,207,151, granted upon my application on December 5, 1916. In various aspects, however, the invention is not 25 restricted in respect to utility to the specific type of machine illustrated in said Letters Patent, and it should be understood that in many of its features the invention is of 30 wide applicability to machines of different types.

The machine shown in said patent is provided with a plurality of forks to receive the buttons when the work is initially presented to the machine, and in the operation 35 of the machine the buttons, while they are positioned in the forks, are clamped by pressure applied oppositely to the top of the head and under the eye of each button to hold the buttons against lateral movement. While the buttons are thus clamped, 40 the forks are withdrawn to leave the lower surfaces of the heads of the buttons clear, and then the buttoning operations are effected by members which force the material 45 at the opposite sides of the respective buttonholes over the heads of the buttons and tuck it under the heads.

In the conditions encountered in operating upon a wide range of work it frequently 50 happens that the eye of a button is not centrally disposed with respect to the button head; and in the operation of the machine upon a button of this character the clamping pressure by which the button is

held during the buttoning operation frequently tends to tip the button into an inclined position relatively to the path of movement of the buttoning members. As a consequence, one of the buttoning members may fail to carry the material far enough 60 to tuck it under the lower edge of the button head, and the buttoning operation will fail with respect to that button. The same condition may result, moreover, from failure of perfect alinement between the opening in 65 the button receiving fork and the clamping plunger which engages the head of the button, by reason of which the pressure of the plunger may be applied at one side of the center of the button head and thus cause the 70 button to tip; or from the fact that the buttons are unevenly spaced on the button piece, which may cause adjacent forks to press laterally against the eyes of the buttons positioned therein in such manner as 75 to tip the buttons and cause them to be clamped in inclined positions, such lateral pressure between the buttons and the forks also tending to spring the forks out of alinement with the plungers. These and 80 other difficulties are very largely increased, and failure of the buttoning operation is therefore more likely to occur, in the operation of the machine upon buttons the heads of which are comparatively wide or flat, 85 or both wide and flat, such, for example, as many styles of garter buttons.

In the type of machine shown in my prior patent, moreover, the buttoning members have movements of equal extent outwardly from the sides of the button clamping plunger to carry the material at opposite sides of a buttonhole to the opposite edges of the button head. In the operation of the machine upon buttons having comparatively wide heads it may result, in case the plunger fails to engage the head centrally, for example, for any of the reasons above mentioned, that one of the buttoning members may fail to move far enough to 95 carry the material to the edge of the button head; and in such case also the buttoning operation will fail with respect to that button.

An important object of this invention 105 accordingly is to increase the efficiency of my prior machine in its operation upon work in which the heads of the buttons are

comparatively wide or flat or in which the buttons are unevenly spaced or some of the buttons are imperfectly shaped. To this end, the invention provides, as an important 5 feature, novel means for positioning a button in such manner as to permit movement of the button in response to the action of the buttoning means in its operation to dispose the material adjacent to a buttonhole 10 in buttoned relation to the button. The illustrated embodiment of the invention includes novel button-positioning means which permits the button to be centralized with respect to the opposite side portions of the 15 buttoning means by lateral movement of the button head in response to the pressure of the buttoning means, or permits the button to be tipped with respect to the buttoning means by the action of the buttoning means 20 at one side or the other of the button head. In the construction shown, moreover, in which clamping pressure is applied to hold the buttons during the withdrawal of the button receiving forks, the pressure on the 25 heads of the buttons is relieved after the forks are withdrawn, in order to permit the buttoning means to centralize the button or to tip it during the buttoning operation. With the button thus free for lateral tipping movement, the final action of the buttoning means will be to dispose the button in substantially upright relation to said means; and in the case of buttons having 30 comparatively wide heads, the buttoning means may first tip the button over into edgewise relation to the buttonhole, thus facilitating the entrance of the head into the buttonhole without the necessity for the buttoning members to move laterally as far 35 as otherwise would be required, the button being finally tipped upright as both members engage under the head.

A further feature of the invention, contributing to effective results particularly in 45 a construction such as that shown in which buttoning means engages under the head of a button to dispose the material adjacent to a buttonhole in buttoned relation to the button, consists in novel means for positioning 50 the button in such manner as to permit it to be lifted as the buttoning means forces the material under the head, thus insuring that the material shall be disposed effectively in buttoned position under the head.

55 In accordance with another feature of the invention, the buttoning means is so disposed in relation to the button while the button is in the initial work receiving means that it tends to maintain the button in its 60 correct position during the withdrawal of the receiving means and after the receiving means is withdrawn. In the construction shown the buttoning members are moved to carry the material adjacent to a buttonhole partially over the sides of the button 65

head while the button is positioned in the receiving fork, and as thus positioned they tend to hold the button against lateral movement and to prevent it from tipping as the fork is withdrawn. In the construction 70 shown, moreover, clamping pressure is applied to the button while it is in the fork in order to insure further against its displacement as the fork is withdrawn, and this pressure is subsequently relieved to insure 75 the successful completion of the buttoning operation at both sides of the button as hereinabove explained.

A further feature of the invention resides in a novel construction of button receiving 80 means through the use of which the buttoning means is permitted to assume an effective holding position at the sides of the button head while the button is in the receiving means.

85 Another feature of the invention consists in novel means for discharging the work from the machine. Since the buttons are not clamped at the time of the completion 90 of the buttoning operation, the tendency is for the buttoning members to retain their hold of the buttons after they have moved under the edges of the button heads. The invention accordingly provides means for forcing the buttons out of the buttoning 95 means, this operation in the construction shown being effected by the action of the button head engaging plungers as the parts are returned to their starting positions.

100 Still another feature of the invention, as applied to a machine having a plurality of instrumentalities for operating in spaced locations on a piece of work consists in novel means for controlling the spacing of the different instrumentalities. In accordance 105 with this feature of the invention power operated mechanism is utilized to space the different instrumentalities, thus avoiding the fatigue which operators frequently experience in effecting the required adjustments by the use of a treadle.

110 Other features of the invention reside in novel means for retaining a button effectively in the button receiving means and for operating the retaining means to facilitate 115 the release of the button from the receiving means at the proper time, and in various details of construction and combinations of parts, all of which will now be described with reference to the accompanying drawings and 120 pointed out in the claims.

125 In the drawings:

Figure 1 is an angular perspective view of the front portion of a machine in which the invention is embodied;

Fig. 2 is a longitudinal vertical section;

Fig. 3 is a bottom plan view of one of the button receiving forks, showing the novel means for retaining the button in the fork;

Fig. 4 is a perspective view showing portions of the structure in disassembled relation and illustrating the manner in which the button retaining means shown in Fig. 5 is controlled;

Figs. 5, 6, 7, 8, 9 and 10 show in side elevation portions of one of the sets of instrumentalities for performing a buttoning operation, illustrating different relative positions of the several coöperating instrumentalities in successive stages of the buttoning operation;

Fig. 11 is a perspective view of the parts shown in Fig. 5, with the parts in the same relative positions;

Fig. 12 is a perspective view of a portion of the mechanism shown in Fig. 6, with the parts in the same relative positions;

Fig. 13 shows in perspective portions of the mechanism shown in Fig. 9, with the parts in the same relative positions;

Fig. 14 is a vertical section on the line 14—14 of Fig. 10;

Fig. 15 is a vertical section showing in detail one of the button head engaging plungers and the associated parts;

Fig. 16 is a perspective view of one of the plungers;

Fig. 17 is a vertical section illustrating the manner in which the pressure on the buttons is relieved, and

Figs. 18 and 19 show in perspective and in section mechanism with which the machine is provided for controlling the spacing of the several sets of coöperating instrumentalities.

The machine herein shown, except as to certain features and details which will be hereinafter specifically described, is substantially the same in its details of construction as the machine shown in United States Letters Patent No. 1,207,729, granted upon my application on December 12, 1916, the machine shown in said patent being a machine of the same general type as that disclosed in the earlier Patent No. 1,207,151, hereinbefore referred to. Only such features of the construction, therefore, as it is necessary to refer to for an understanding of the present invention will be described herein in detail, and for further information with reference to the details of the construction shown reference may be made to said prior patents.

The illustrative machine is designed to button a plurality of buttons substantially simultaneously, and to this end is provided with a plurality of sets of coöperating instrumentalities, each set being designed to perform a buttoning operation with respect to a button and a buttonhole. Three sets of such instrumentalities are herein shown, but it will be understood that in machines of this type the number of sets of such instrumentalities may be varied as desired, in

accordance with the number of the buttoning operations which it is desired to perform in one operation of the machine.

Each of the sets of instrumentalities consists of a button-receiving fork 2, button-hole fly positioning means comprising a supporting member 4 and buttonhole spreaders 6 positioned above the fork 2, button holding or positioning means comprising an anvil 8 and a button head engaging plunger 10, and buttoning means comprising members 12 positioned on opposite sides of the plunger 10 and operated to force the material at opposite sides of a buttonhole over the sides of a button head and to tuck it under the edges of the button head. In the operation of this type of machine, generally stated, the buttons are positioned initially in the forks 2 with the forks projecting between the button piece and the lower sides of the button heads, and the buttonhole fly is positioned upon the supporting members 4 with the spreader blades 6 projecting into the buttonholes. When the machine is started the buttonhole fly positioning means is moved rearwardly to cause the buttonholes to align with the plungers 10, the several pairs of spreader blades 6 being separated during this movement in order to open the buttonholes. The plungers 10 then move downward into the open buttonholes, and simultaneously the spreader blades 6 are moved downward out of the buttonholes and these blades, together with the members 4, are moved backward to inoperative positions. By continued downward movement of the plungers 10 these plungers are carried into engagement with the tops of the button heads, and the anvils 8 are moved upward into position to engage the button piece under the eyes of the buttons, the plungers and the anvils thus clamping the buttons between them. Subsequently, in the operation of the illustrative type of machine, the buttoning members 12 are operated to perform the buttoning operations by forcing the material at opposite sides of the buttonholes over the heads of the buttons and tucking it under the heads, the forks 2 being withdrawn to an inoperative position while the buttons are clamped by the members 8 and 10, in order to clear the lower sides of the buttons and leave room for the material adjacent to the buttonholes to be disposed in buttoned position under the heads of the buttons.

Each of the forks 2, in the construction shown, is carried on the front end of a slide bar 14, the several bars 14 being connected at their rear ends to an operating slide 16 which is operated from a cam 18 on the main shaft 20 through connections including a link 22 and a lever 24 fulcrumed on a shaft 26, the lever carrying a roll 28 in engagement with the cam. The buttonhole fly sup-

porting members 4 are operated in substantially the same manner as the forks 2, these members being carried at the front ends of slide bars 30 which rest upon the bars 14. 5 The rear ends of the bars 30 are connected to an operating slide 32 which is connected by a link 34 to a lever 36 fulcrumed on the shaft 26 and carrying a roll 38 which engages a cam 40 on the shaft 20.

10 The buttonhole spreaders of each set comprise a pair of spreader arms 42 (Fig. 4) located below the member 4 and pivoted for closing and opening movements on a shell 44 which is pivoted at 46 to the bar 30. Each 15 arm 42 carries at its outer end one of the up-standing blades 6, these blades being positioned normally close to each other for engagement in a buttonhole by spring means arranged to operate upon the arms 42 and 20 not shown herein in detail. During the backward movement of the bars 30 to carry the buttonholes into alinement with the plungers 10 the arms 42 are forced apart by 25 sliding engagement with pins 48 on the bars 14, these pins being normally positioned in slots 50 formed in the adjacent faces of the arms 42. This causes the blades 6 to open the buttonholes and to hold them open for the reception of the plungers 10. In order 30 to withdraw the spreader blades 6 from the buttonholes, the shells 44 are swung about their pivots 46 by engagement of the rear end portions of the shells with inclined faces 52 on the bars 14 during continued backward movement of the bars 30 relatively to 35 the bars 14.

Each of the plungers 10 is slidably mounted in a sleeve 54 which is secured in a holder 56 by means of a nut 58. The several holders 56 are mounted for movement with a 40 vertically reciprocating head 60 which is mounted in guideways on the machine frame and is operated to lower and raise the holders 56 by means of a bell crank fulcrumed 45 on a shaft 62, this bell crank having two forwardly extending arms 64 connected respectively to opposite ends of the head 60, and a rearwardly extending arm 66 which carries a roll 68 in engagement with a cam 70. In 50 order to prevent relative movement between the plungers 10 and the sleeves 54 when the holders 56 are lowered to carry the plungers into engagement with the buttons, and thus to cause pressure to be firmly applied on the 55 tops of the button heads, the machine is provided with a strap 72 arranged to overlie the upper ends of the several plungers and to move downwardly in unison with the holders 56. The strap 72 is secured to the 60 forward ends of a pair of arms 74 which comprise a portion of a bell crank fulcrumed on a shaft 76 on the movable head 60 and having a rearwardly extending arm 78. Springs 79 connected at their opposite ends 65 respectively to the arms 74 and to hooks on

the head 60 tend to pull the strap 72 downward and thus to hold it in position to prevent relative movement between the plungers 10 and the holders 56. The arm 78 has a pin and slot connection with the forwardly 70 extending arm 80 of a second bell crank which is fulcrumed on the shaft 62, the rearwardly extending arm 82 of this bell crank carrying a roll 84 which is in position to be engaged during a portion of the cycle of operations of the machine by an operating cam 86 on the cam shaft 20. At a certain stage in the cycle of operations of the machine the strap 72 is thus lifted from the upper ends 80 of the plungers 10 against the tension of the springs 79 in order to relieve the clamping pressure on the buttons.

In order to insure that the clamping pressure shall be applied to the heads of all the buttons notwithstanding any variations 85 which there may be in the height of the button heads, yielding connections are afforded between the strap 72 and the several plungers 10 through the provision of pins 88 mounted in caps 90 secured by means of set screws 92 to the upwardly extending shank portions of the plungers 10, the pins 88 being upheld by means of springs 94 mounted in sockets therein and engaging the upper ends of the plungers 10. The 90 clamping pressure upon the tops of all the buttons is thus a yielding one, through the provision of both the springs 79 and the springs 94, and through the provision for 95 relative yield of the several pins 88 effective 100 pressure upon the heads of all the buttons is insured.

The anvils 8 are adjustably mounted on the end portions of forwardly extending bars 96 which are detachably pivoted on a 105 transverse bar 98. The operating means for raising and lowering the anvils comprises a yoke 100 fulcrumed on a shaft 102, this yoke carrying a cross bar 104 in which is adjustably mounted a bar 106 which 110 underlies the several bars 96 intermediate between their opposite ends. The yoke 100 is raised and lowered by means of a toggle comprising links 108 and 110, the link 108 being connected to the yoke and the link 110 fixed on a rock shaft 112 to which is secured an arm 114 (Fig. 1), this arm being connected by a rod 116 to an arm 118 (Fig. 2), which carries a roll 120 in engagement with a cam 122 on the cam shaft 20. Upon 120 movement of the rod 116 in the direction to straighten the toggle, the yoke 100 is lifted to swing the several bars 96 into position to cause the anvils 8 to engage the button piece under the eyes of the buttons.

In order to insure that the buttons in the forks 2 shall be alined with the plungers 10 at the time when the buttons are clamped between the plungers 10 and the anvils 8, the machine is provided with a gripper for 130

engaging the button piece, comprising an upper jaw 124 carried at the front end of a slidable bar 126 and a lower jaw 128 pivoted at 130 on an arm 132 which is pivotally mounted at 134 on the bar 126. Between the jaw 128 and the arm 132 is a spring 136 through the provision of which the clamping pressure of the jaw 128 on the button piece is a yielding one. The bar 126 is 5 ably supported on a fixed portion of the machine beneath the bar 14 of the central set of operating instrumentalities. Conveniently the gripper is arranged to be moved in unison with the backward movement of 10 the buttonhole fly positioning means, and to this end the bar 126 is connected by means of a rod 138 to the lever 36 by which the bars 30 are operated. In order to cause the gripper to be closed upon the stock by 15 the backward movement of the bar 126, the arm 132 is provided with a depending projection 140 which rests upon the central anvil bar 96 and during the backward movement of the bar 126 engages a cam block 20 142 on the anvil bar. During the first part of the backward movement of the bar 126 the arm 132 is thus forced upwardly by the cam block 142 to cause the jaw 128 to close 25 upon the stock and in co-operation with the jaw 124 to grip it yieldingly, and during 30 the continued backward movement of the gripper the button piece is drawn backwardly to insure that the buttons shall be positioned at the inner ends of the openings 35 in the forks.

Each of the holders 56 carries a pair of buttoning members or tuckers 12 hereinbefore referred to, these two members being positioned on opposite sides of the plunger 40 10 for engagement with the material at opposite sides of a buttonhole at the edges of the buttonhole. The two members 12 are pivoted on plates 146 secured to the holder 56 and are held in yielding engagement with 45 the plunger 10 by means of a spring 148, the opposite end portions of which bear upon the respective members. Each buttoning member or tucker is provided with an in-turned end portion 150, the inner edge of 50 which is curved in substantial conformity to the curve of the head of a button and in the buttoning operation is arranged to slide under the head of the button to tuck the stock into buttoned position under the head. 55 Each of the members is also provided with a spur 152 for engagement with the edge binding stitches of the buttonhole, in order to insure that the member shall remain in effective engagement with the material at 60 the edges of the buttonhole during the buttoning operation. Each buttoning member has also an inwardly extending projection 154 for engagement in slots 156 and 158 formed in the adjacent side of the plunger 65 10, these slots being separated by a cam

portion 160 of the plunger. Normally the projections 154 are seated in the slots 156 with the lower ends of the buttoning members raised above the lower end of the plunger 10, as shown in Fig. 2. To perform the 70 buttoning operation the buttoning members are moved downward by downward movement of the holder 56 relatively to the plunger 10, and in this downward movement of the buttoning members the projections 154 75 are engaged by the cam portions 160 of the plunger to cause the members to be forced outwardly and thus to carry the material at the opposite sides of the buttonhole toward the sides of the button head during the 80 downward movement of the members, the spurs 152 at this time maintaining an effective hold upon the inner edges of the buttonhole. During the continued downward movement of the buttoning members 85 the material is carried over the sides of the head of the button, and finally the projections 154 are forced into the slots 158 by the action of the spring 148 to cause the lower end portions of the buttoning members 90 to move inward under the head of the button and tuck the material into buttoned position, as shown in Fig. 14.

In order to provide for adjustment of the several sets of operating instrumentalities 95 for operating upon differently spaced buttons and buttonholes, the several sets, with the exception of the central set, are arranged for simultaneous lateral adjusting movements. To this end the bars 14, 30 and 96 100 of each set, with the exception of the central set, are mounted for simultaneous lateral movement through the provision of means substantially as shown and described in the prior Patent No. 1,207,729. The adjusting 105 mechanism of the several sets, as fully described in said prior patent, comprises a series of links 162 pivotally connected to a lever 164 which has a pin and slot connection with a sliding controller member 166. 110 The controller member 166 is also connected with the corresponding holders 56 which carry the plungers 10 and the buttoning members, as described in said prior patent. The controller member 166 is operated by a 115 bell crank 168 fulcrumed on the frame of the machine at 170 and provided with a segmental gear 172 which engages a companion gear carried by an arm 174 of another bell crank which is fulcrumed at 176, 120 the rearwardly extending arm 178 of this bell crank being connected to an operating rod 180. Adjusting movement of the several movable sets of instrumentalities is thus effected by lengthwise movement of the rod 125 180 in one direction or the other to increase or diminish respectively the spaces between the several sets to correspond to differences in the spacing of the buttons and the buttonholes. 130

In order to relieve the operator of unnecessary fatigue and to facilitate the adjustments above described, the machine is provided with power means for operating the rod 180. To this end two friction clutch disks 182 (Figs. 18 and 19), arranged to be driven by belts respectively in opposite directions, are mounted loosely on a shaft 184 supported for lengthwise sliding movement in bearings in a bracket 186 secured in any convenient location underneath the head portion of the machine. Secured on the shaft 184 between the disks 182 is a co-operating clutch disk 188. At one end 15 the shaft 184 carries a crank disk 190 to which the rod 180 is connected at its lower end, the disk 190 being provided with lugs 192 arranged to engage a portion of the bracket 186 in order to limit turning movement of the shaft 184 to substantially a 20 half revolution. Lengthwise movement is imparted to the shaft 184 by means of a bell crank 194 pivoted on the bracket 186, a downwardly extending arm of this bell 25 crank having an operating connection with the shaft 184, and the other arm of the bell crank being connected to a treadle rod 196 operated by a treadle 198. During the operation of the machine the operator rests 30 one foot upon the treadle 198, and when adjustment of the spacing of the several sets of instrumentalities is necessary, moves the treadle in one direction or the other, depending upon whether the distances between 35 the sets are to be increased or diminished. This causes the clutch disk 188 to engage one or the other of the disks 182 and receive operative movement to force the rod 180 in the required direction, the extent of the 40 movement being readily under the control of the operator. It will be understood that the different sets are retained in any position to which they may be adjusted through the normal friction between the various 45 parts. In case the treadle 198 should be accidentally operated in such manner as to hold the clutch disk 188 too long in engagement with one of the disks 182, one or the other of the lugs 192 will engage the bracket 50 186 to limit the turning movement of the shaft 184 and thus cause a slip between the co-operating clutch disks and avoid carrying the sets of instrumentalities too far in such manner as to strain any portion of the 55 machine.

Each of the button receiving forks 2, as shown clearly in Fig. 4, is provided around its button receiving slot with a comparatively narrow upraised projection 200 which 60 engages under the head of the button and lifts the head above the plane of the upper surface of portions of the fork which extend beyond the sides of the button, this projection being sufficiently narrow to prevent it 65 from extending materially beyond the side

edges of the button head. This construction facilitates the operation of the buttoning means in a manner which will be hereinafter explained.

In order to insure that the several buttons shall be retained in the button receiving forks 2 when the work is presented to the machine, and particularly to prevent them from slipping out of the forks as the operator positions the buttonhole fly upon the supports 4, the two end forks of the series are each provided with a finger or catch 202 (Fig. 3) pivoted on a pin 204 on the lower side of the fork and shaped to engage the eye of the button and retain it in the 75 fork. The rear end portion of the finger 202 is arranged to engage a flange 206 on the fork to limit the movement of the finger. Pivoted also on the pin 204 is a controlling member 208 which is arranged to engage a 80 flange 210 on the opposite side of the fork, and between the member 208 and the rear end portion of the finger 202 is a spring 212 which tends to hold the front end of the finger 202 in button retaining position while 85 permitting the eye of the button readily to slip by the finger when the fork is withdrawn. In order to insure that the buttons shall be retained in the forks when the parts of the machine are in starting position and 90 during the movement of the buttonhole fly to position it upon the supports 4, means is provided for operating the controlling member 208 to increase the tension of the spring 212. For this purpose the member 208 carries a pin 214 which projects through a slot in the bar 14 in position to be engaged by a cam surface 216 on one of the shells 44 which, in the normal relation of the parts, 95 is positioned directly above the pin 214. The member 208 is thus held normally in a position farther to the left than indicated in Fig. 3, causing the tension of the spring 212 to be increased for holding the finger 202 in button retaining position. When the shells 44 are withdrawn by the backward movement of the bars 30, the pins 214 are 100 released, thereby decreasing the tension of the springs 212 before the forks are withdrawn from the buttons.

In the operation of the machine, the button piece is inserted between the open gripper jaws 124 and 128 and the buttons are inserted in the openings of the forks 2 with the heads of the buttons resting upon the 105 projections 200. The buttonhole fly is then positioned upon the supports 4 with the spreader blades 6 projecting through the buttonholes, as shown in Fig. 5. The machine is then started by the actuation of the 110 usual clutch.

During the first part of the operation of the machine the bars 30 are drawn backwardly, carrying the buttonhole fly into position to cause the buttonholes to align with 115

the respective plungers 10. During this movement the spreader blades 6 are forced apart by the wedging action of the pins 48 upon the arms 42. Simultaneously also the 5 bar 126 is drawn backwardly, causing the gripper jaws to seize the button piece. The relative positions of the parts at the end of this stage of the cycle of operations are shown in Figs. 6 and 12.

10 The head 60 and the strap 72 are next lowered, the strap being held by the springs 79 in operative relation to the plungers 10, this movement carrying the plungers 10 and the buttoning members 12 downwardly 15 and causing the plungers to enter the buttonholes which are held open by the spreader blades 6. After the plungers have entered the buttonholes, further backward movement of the bars 30 causes the spreaders 6 to be swung downwardly out of the buttonholes by reason of the engagement of the shells 44 with the inclines 52 on the bars 14, and the spreaders 6 and the button-hole fly supports 4 are then drawn backwardly away from the buttonholes, as shown 20 in Fig. 7. Simultaneously movement is imparted to the gripper to insure the positioning of the buttons at the inner ends of the openings in the fork. By the continued 25 downward movement of the head 60 and the strap 72 the plungers 10 are carried into engagement with the heads of the buttons, the spring pins 88 yielding as required to permit all the plungers to engage the button 30 heads with effective pressure; and during the latter portion of the downward movement of the plungers the anvils 8 are moved upward into position to engage the button piece and to cause the several buttons to be 35 clamped between the plungers 10 and the anvils 8 as shown in Fig. 8, the supports 4 being still farther withdrawn to their inoperative positions.

At this stage in the cycle of operations 40 downward movement of the strap 72 ceases by reason of the engagement of the plungers 10 with the buttons, while continued downward movement of the head 60 and the holders 56 relatively to the plungers 10 45 causes the buttoning members 12 to push the buttonhole fly toward the heads of the buttons. As the buttoning members engage the buttonhole fly, the spurs 152 enter the buttonholes at opposite sides of the 50 plungers 10 in engagement with the edge binding stitches, and when the projections 55 on the buttoning members engage the cam portions 160 of the plungers, the buttoning members are separated to carry the 60 material at the edges of the buttonholes outward toward the sides of the button heads during the movement of the material downward over the heads. When the lower 65 end portions of the buttoning members have arrived substantially at the opposite sides

of the button heads, as indicated in Fig. 9, downward movement of the head 60, and consequently of the buttoning members, ceases. The movement of the buttoning members to permit them to engage the buttons thus substantially at the sides of the heads and near the lower edges of the heads is permitted by reason of the fact that the buttons are supported by the projections 70 200 above the plane of the side portions of the forks, thereby affording sufficient space between the lower ends of the buttoning members and the forks for the thickness of the buttonhole fly.

While the buttoning members are positioned at opposite sides of the button heads as shown in Fig. 9, and thus tend to hold the buttons against lateral movement, the forks 2 are drawn backwardly from between the surface of the button piece and the lower 80 sides of the button heads. In the construction shown the clamping pressure of the plungers 10 and the anvils 8 upon the buttons is also maintained as the forks start to move backwardly, thus further insuring 85 against any displacement of the buttons out of alignment with the plungers 10 and the buttoning means. When the forks have moved to such a position that there is no further tendency to displace the buttons, the 90 strap 72 is lifted by means of its operating cam 86, as shown in Fig. 17, thus causing the plungers 10 to release their pressure upon the button heads, the plungers, however, continuing to rest upon the button heads in 95 position to serve as guides for the buttoning members. After the clamping pressure on the buttons is thus relieved, the button heads are free for lateral movement, and in case 100 any of the buttons have not been positioned 105 in correct alignment with the plungers, the buttoning members at the sides of the button heads are then rendered effective to centralize the buttons with respect to the plungers and the buttoning means. While the 110 buttons are still supported by the anvils 8 and are free to tip or to move laterally, further downward movement is imparted to the buttoning members 12 by the operation of the head 60, the members thus forcing the 115 material at the sides of the buttonholes farther downward, and as the projections 154 enter the slots 158 the lower end portions of the members are forced inwardly under the heads of the buttons by the action of the 120 springs 148, as shown in Figs. 10 and 14, thus insuring that the material at the sides of the buttonholes shall be tucked into buttoned position under the heads of the buttons. In case, for any of the reasons herein- 125 before mentioned, any of the buttons may have been clamped between the plungers 10 and the anvils 8 in inclined positions, the buttoning members, after the pressure of the plungers 10 is relieved, are rendered effec- 130

tive by engagement with the sides and under the edges of the buttons during their final downward movement to tip the buttons to an upright position with respect to the button 5 toning means and thus to insure that the material at both sides of the buttonholes shall be effectively buttoned. In the case of buttons with unusually wide heads, moreover, the buttons may first be tipped into edge- 10 wise relation to the buttonholes by relatively greater effective pressure of one of the buttoning members on one side portion of the button, the entrance of the button into the buttonhole being thus facilitated, 15 after which the button is tipped to an upright position in symmetrical relation to both buttoning members. Since there is no substantial pressure upon the tops of the buttons at the time of the final downward 20 movement of the buttoning members, the buttons are free to be lifted when these members snap under the button heads, as indicated in Fig. 14, this provision for lifting of the buttons serving as additional insurance 25 that the sides of the button heads shall clear the edges of the buttonholes and that the material at the sides of the buttonholes shall be tucked securely under the button heads.

30 Upon the completion of the buttoning operation the tendency of the spring held buttoning members 12 is to retain the buttons in the position shown in Fig. 14. During the return of the parts to starting position, 35 however, the plungers 10 are again carried into operative relation to the strap 72, the upward movement of which is limited by a stop 218. During the continued upward movement of the head 60 after the movement of the plungers 10 is stopped in this manner, the buttoning members 12 are pulled upwardly away from the buttons and the buttons are thus discharged from the machine by the action of the plungers 10 on 45 the heads.

Having described the invention, what I claim as new and desire to secure by Letters Patent of the United States is:—

1. A buttoning machine having, in combination, buttoning means movable in engagement with the material adjacent to a buttonhole to force said material over the head of a button, and means for positioning the button for the buttoning operation, said button positioning means being organized to permit the button to be tipped by the action of the buttoning means.

2. A buttoning machine having, in combination, buttoning members arranged to engage the material at opposite sides of a buttonhole, mechanism for operating said members to cause them to force the material at the opposite sides of the buttonhole over the head of a button, and means for positioning 60 the button for the buttoning operation, said

button positioning means being organized to permit the button to tip in either direction in response to the pressure of said members.

3. A buttoning machine having, in combination, buttoning means arranged to engage the material at opposite sides of a buttonhole, mechanism for moving said buttoning means over the sides of the head of a button, and means for positioning the button for the buttoning operation, said button positioning means being organized to permit the button to be tipped by the action of the buttoning means when the buttoning means is positioned substantially at the sides 75 of the button head.

4. A buttoning machine having, in combination, means for engaging a buttonhole fly adjacent to a buttonhole, means for positioning a button, and mechanism for relatively 85 moving said buttonhole fly engaging means and button positioning means to cause said fly engaging means to force the material at opposite sides of the buttonhole over the button head and to engage under opposite 90 sides of the head to dispose said material in buttoned position, said button positioning means being organized to permit the button head to be moved laterally by the action of the buttonhole fly engaging means. 95

5. A buttoning machine having, in combination, buttoning means arranged to engage the material at opposite sides of a buttonhole, mechanism for moving said buttoning means over the sides and under the edges of 100 the head of a button to dispose the material in buttoned relation to the button, and means for positioning the button for the buttoning operation, said button positioning means being organized to permit the button to tip 105 in response to pressure of the buttoning means.

6. A buttoning machine having, in combination, buttoning means movable in engagement with the material at opposite edges of 110 a buttonhole to open the buttonhole and force said material over the head of a button, and means for supporting the button in such manner as to permit the head of the button to be moved laterally by the action of 115 said buttoning means.

7. A buttoning machine having, in combination, buttoning means movable in engagement with the material at opposite edges of a buttonhole to force the material over the 120 head of a button at opposite sides of the head, and means for positioning the button for the buttoning operation, said button positioning means being organized to permit the button head to move laterally in 125 either direction in response to pressure of the buttoning means at the opposite sides of the head.

8. A buttoning machine having, in combination, buttoning means movable in engage- 130

ment with the material at opposite edges of a buttonhole to dispose said material in buttoned relation to a button, and means for positioning the button in such manner as to 5 permit the button to be centralized relatively to the buttoning means by the action of said buttoning means.

9. A buttoning machine having, in combination, buttonhole fly engaging means, button 10 ton positioning means, and mechanism for effecting relative movement of said means to cause the buttonhole fly engaging means to force the material adjacent to a buttonhole over the head of a button and to move under 15 the head to dispose said material in buttoned position, said button positioning means being constructed and arranged to support the button by engagement with the button piece under the eye of the button in 20 such manner as to permit the button to be lifted by the action of the buttonhole fly engaging means as said means moves under the button head.

10. A buttoning machine having, in combination, buttoning means movable in a direction substantially perpendicular to the plane of a button piece about a button to force the material adjacent to a buttonhole over the head of the button and movable also to dispose the material under the head, and means 30 for supporting the button in such manner as to leave the button free to be lifted by the buttoning means.

11. A buttoning machine having, in combination, buttoning means comprising opposed members movable apart and downwardly to force the material adjacent to a buttonhole over the head of a button and movable toward each other under the button 40 head to dispose the material in buttoned relation to the button, and means for supporting the button in such manner as to permit the button to be lifted by said members as they move under the button head.

45 12. A buttoning machine having, in combination, buttoning means comprising opposed members movable toward each other under the edges of a button head at opposite sides of the button to dispose the material 50 adjacent to a buttonhole in buttoned relation to the button, and means for supporting the button in such manner as to permit the button to be lifted by said members.

13. A buttoning machine having, in combination, means for engaging a buttonhole fly adjacent to a buttonhole, means for positioning a button, and mechanism for relatively moving said buttonhole fly engaging means and said button positioning means to 60 perform a buttoning operation, said button positioning means being organized to permit the button to be tipped into edgewise relation to the buttonhole by the action of said buttonhole fly engaging means.

65 14. A buttoning machine having, in com-

bination, buttoning means arranged to engage the material at opposite sides of a buttonhole, mechanism for operating said buttoning means to cause said means to force said material over the head of a button, and 70 means for positioning the button for the buttoning operation, said button positioning means being organized to permit the button to be tipped into edgewise relation to the buttonhole by the action of said buttoning 75 means.

15. A buttoning machine having, in combination, buttoning means movable over the head of a button at opposite sides of the head and into position to engage under opposite sides of the head to dispose the material adjacent to a buttonhole in buttoned relation to the button, and means for positioning the button in such manner as to permit the button to be tipped to an upright 80 position relatively to the buttoning means by the pressure of said means on opposite sides of the head.

16. A buttoning machine having, in combination, buttoning means having a determined range of movement to force the material at opposite sides of a buttonhole over the head of a button and to tuck the material under the edges of the button head, and means for positioning a button in such 95 manner as to permit the button to be tipped to an upright position relatively to the buttoning means by the pressure of said means at opposite sides of the head to insure tucking the material under the head at both 100 sides.

17. A buttoning machine having, in combination, buttoning members movable in engagement with the material at opposite sides of a buttonhole to force the material over 105 the head of a button and then toward each other under the edges of the button head, and means for positioning the button in such manner as to permit the button to be lifted by said members as they move under 110 the button head.

18. A buttoning machine having, in combination, buttoning members for engaging the material at opposite sides of a buttonhole, spring means tending to move said 115 members toward each other, means for operating said members to cause them to carry the material outwardly and downwardly over the sides of the head of a button and then to permit them to move under the button head in response to the action of said spring means, and means for positioning a button in such manner as to permit it to be lifted when said members move under the head. 120

19. A buttoning machine having, in combination, buttoning means movable over the head of a button at opposite sides of the head and into position to engage under opposite sides of the head to force the material 130

- at opposite sides of a buttonhole over the head and dispose it in buttoned relation to the button, and means for positioning a button in such manner as to permit it to be tipped relatively to the buttoning means by the pressure of said buttoning means at opposite sides of the head and to be lifted by the engagement of said means under the head.
- 10 20. A buttoning machine having, in combination, buttoning means arranged to engage the material adjacent to a buttonhole, means for supporting a button by engagement with the button piece under the eye of the button while leaving the button free for lateral movement of the button head, and mechanism for effecting relative movement of said buttoning means and button supporting means to perform the buttoning operation.
- 15 21. A buttoning machine having, in combination, buttoning means movable in engagement with the material at opposite sides of a buttonhole to dispose said material in buttoned relation to a button, and means for supporting the button by engagement with the button piece under the eye of the button while leaving the button free to tip in the buttoning operation.
- 20 22. A buttoning machine having, in combination, buttoning members movable to force the material adjacent to a buttonhole over opposite sides of the head of a button, and means for supporting the button by engagement with the button piece under the eye of the button in such manner as to permit the button to be tipped in either direction by the action of said buttoning members.
- 25 23. A buttoning machine having, in combination, buttoning means movable to force the material adjacent to a buttonhole over opposite sides of the head of a button, and means for supporting the button by engagement with the button piece under the eye of the button in such manner as to permit the head of the button to be moved laterally in either direction by the pressure of said buttoning means.
- 30 24. A buttoning machine having, in combination, buttoning means movable in engagement with a buttonhole fly into position under the edges of the head of a button to dispose the material adjacent to a buttonhole in buttoned relation to the button, and means for supporting the button by engagement with the button piece under the eye of the button in such manner as to permit the button to be lifted by the buttoning means.
- 35 25. A buttoning machine having, in combination, buttonhole fly engaging means, means for positioning a button by pressure applied on the top of the button head, mechanism for relatively moving said buttonhole
- fly engaging means and button positioning means to perform a buttoning operation, and means for relieving the pressure on the button head before the buttoning operation is completed.
- 40 26. A buttoning machine having, in combination, buttoning means movable in engagement with a buttonhole fly to dispose the material adjacent to a button, means for positioning the button by pressure applied on the button head, and means for relieving said pressure during the buttoning operation.
- 45 27. A buttoning machine having, in combination, buttoning means movable to force the material adjacent to a buttonhole over the opposite sides of the head of a button, means for positioning the button by pressure applied on the top of the button head, and means for relieving said pressure when the buttoning means is positioned at the sides of the button head.
- 50 28. A buttoning machine having, in combination, button positioning means organized to hold a button by pressure applied on the top of the button head, means for forcing the material of a buttonhole fly over the sides of the button head and into buttoned position under the head, and means for causing the pressure on the head to be relieved when the material is forced over the head.
- 55 29. A buttoning machine having, in combination, buttoning means movable downwardly over the sides of the head of a button to force the material adjacent to a buttonhole over the button head, means for positioning the button by pressure applied on the top of the button head, and means for relieving said pressure to permit the button to be tipped by the pressure of said buttoning means at the sides of the head.
- 60 30. A buttoning machine having, in combination, buttoning means movable in engagement with a buttonhole fly into position under the head of a button to dispose the material in buttoned relation to the button, means for positioning the button by pressure applied on the top of the button head, and means for relieving said pressure to permit the buttoning means to centralize the button and to engage uniformly under opposite sides of the button head.
- 65 31. A buttoning machine having, in combination, buttoning means movable to force the material adjacent to a buttonhole over the head of a button and to dispose it under the button head in buttoned relation to the button, means for positioning the button by pressure applied on the top of the button head, and means for relieving said pressure at an intermediate stage in the buttoning operation.
- 70 32. A buttoning machine having, in combination, buttoning means movable to force

the material at opposite sides of a button-hole over the sides of the head of a button and then movable under the head to dispose the material in buttoned relation to the 5 button, means for positioning the button by pressure applied on the button head, and means for relieving said pressure when the buttoning means is positioned at the sides of the head and before it engages under the 10 head.

33. A buttoning machine having, in combination, buttoning means movable in engagement with a buttonhole fly into position under the head of a button to dispose the 15 material adjacent to a buttonhole in buttoned relation to the button, means for positioning the button by pressure applied on the top of the button head, and means for relieving said pressure to permit the button 20 to be lifted by the buttoning means.

34. A buttoning machine having, in combination, buttoning means arranged to engage a buttonhole fly adjacent to a buttonhole, button positioning means arranged 25 to clamp a button by pressure applied on the button head and under the eye of the button, mechanism for relatively moving said buttoning means and button positioning means to perform a buttoning operation, 30 and means for relieving the clamping pressure on the button to permit the button head to move laterally in the buttoning operation.

35. A buttoning machine having, in combination, buttoning means movable to force 35 the material at opposite sides of a buttonhole over the head of a button, means for clamping the button by engagement with the top of the button head and with the button piece under the eye of the button to position the 40 button for the buttoning operation, and means for relieving the pressure of said clamping means on the button to permit the button to tip during the buttoning operation.

36. A buttoning machine having, in combination, buttoning means movable to force 45 the material at opposite sides of a button-hole over the head of a button and to dispose it under the edges of the button head, means for clamping the button by engagement with the top of the button head and with the button piece under the eye of the button to position the button for the buttoning operation, and means for relieving the 50 clamping pressure on the button at an intermediate stage in the buttoning operation.

37. A buttoning machine having, in combination, means for positioning a button by pressure applied on the top of the button head, buttoning means arranged to engage a 60 buttonhole fly at opposite sides of a button-hole, mechanism for moving said buttoning means to force the material of the button-hole fly partly over the head of the button while the button is thus held under pressure,

and means for relieving the pressure on the 65 button head before the buttoning operation is completed.

38. A buttoning machine having, in combination, means for positioning a button by pressure applied on the top of the button 70 head, means for relieving the pressure on the button head at an intermediate stage in the buttoning operation, buttoning means arranged to engage a buttonhole fly at opposite sides of a buttonhole, and mechanism 75 for operating said buttoning means to force the material partly over the head of the button while the button is thus held under pressure and to dispose the material under the edges of the button head after the pressure 80 is relieved.

39. A buttoning machine having, in combination, buttoning means movable to force the material at opposite sides of a button-hole over the head of a button, means for 85 supporting the button beneath the button eye, means for applying pressure on the top of the button head to hold the button on said supporting means against lateral movement, and means for relieving the pressure 90 on the button head at an intermediate stage in the buttoning operation.

40. A buttoning machine having, in combination, a button support, a plunger for engaging the head of a button on said support, 95 means for applying pressure to said plunger to hold the button on the support against tipping movement, buttoning means movable to force the material adjacent to a buttonhole over the head of the button and to 100 dispose it under the edges of the button head, and means for relieving the pressure on the head of the button when said buttoning means has partially completed the buttoning operation.

41. A buttoning machine having, in combination, a button support, a plunger for engaging the head of a button on said support, 110 means for applying pressure to said plunger to hold the button on the support, buttoning means movable into position under the edges of the head of the button to dispose the material adjacent to a buttonhole in buttoned relation to the button, and means for relieving the pressure on said plunger 115 to permit the button to be lifted by said buttoning means.

42. A buttoning machine having, in combination, a member arranged to engage in a buttonhole and to position a button by pressure applied on the button head, buttoning means movable to force the material at opposite sides of the buttonhole over the button head, and means for relieving the pressure of said member on the button head at 120 an intermediate stage in the buttoning operation.

43. A buttoning machine having, in com-

bination, a plunger arranged to engage in a buttonhole and to position a button by pressure applied on the button head, tuckers movable lengthwise of said plunger to force 5 the material at opposite sides of the buttonhole over the button head and then under the edges of the button head to dispose the material in buttoned relation to the button, and means for relieving the pressure of said 10 plunger on the button head at an intermediate stage in the buttoning operation.

44. A buttoning machine having, in combination, buttonhole fly engaging means, means for holding against tipping movement 15 a button attached to a button piece, mechanism for relatively moving said means to perform a buttoning operation, and means for releasing the button to permit it to tip before the buttoning operation is completed.

20 45. A buttoning machine having, in combination, means for clamping against tipping movement a button attached to a button piece, buttonhole fly engaging means, mechanism for relatively moving said means to 25 perform a buttoning operation, and means for relieving the pressure of the clamping means on the button before the buttoning operation is completed.

46. A buttoning machine having, in combination, button receiving means, buttonhole fly engaging means, mechanism for relatively moving said means in such manner as to force the material adjacent to a buttonhole partially over the head of a button 30 35 while the button is positioned by said receiving means, means for withdrawing said receiving means from receiving position, and means for completing the buttoning operation after the withdrawal of said receiving 40 means is initiated.

47. A buttoning machine having, in combination, button receiving means, buttonhole fly engaging means, mechanism for operating said buttonhole fly engaging means to force 45 the material adjacent to a buttonhole partially over the head of a button while the button is positioned by said receiving means, means for withdrawing said receiving means from receiving position, and mechanism for 50 operating the buttonhole fly engaging means to complete the buttoning operation after said receiving means is withdrawn.

48. A buttoning machine having, in combination, button receiving means arranged 55 to position a button when the work is initially presented to the machine, means for withdrawing said receiving means subsequently from receiving position, buttoning members arranged to engage the material 60 at opposite sides of a buttonhole, and mechanism for operating said members in two stages to cause them to force the material partially over the button head while the button is positioned by said receiving means

and to tuck the material under the edges of 65 the button head after the receiving means is withdrawn.

49. A buttoning machine having, in combination, a fork arranged to receive a button attached to a button piece when the work 70 is initially presented to the machine, means for withdrawing said fork subsequently from receiving position, buttoning means arranged to engage a buttonhole fly adjacent to a buttonhole, and mechanism for operating 75 said buttoning means to cause it to force the material partially over the button head while the button is positioned in said fork and to complete the buttoning operation after the fork is withdrawn. 80

50. A buttoning machine having, in combination, a fork arranged to receive a button attached to a button piece when the work is initially presented to the machine, means for withdrawing said fork subsequently from 85 receiving position, tuckers arranged to engage a buttonhole fly at opposite sides of a buttonhole, and mechanism for operating said tuckers to cause them to force the material out to the sides of the button head 90 while the button is positioned in said fork and to tuck the material under the button head after the fork is withdrawn.

51. A buttoning machine having, in combination, button receiving means arranged to 95 position a button attached to a button piece when the work is initially presented to the machine, means for withdrawing said receiving means subsequently from receiving position, means for holding the button against 100 lateral movement during the withdrawal of said receiving means, means for performing a buttoning operation with respect to the button, and means for operating said holding means to release the button before the 105 buttoning operation is completed.

52. A buttoning machine having, in combination, button receiving means, means for clamping a button in said receiving means by pressure applied on the top of the head 110 and under the eye of the button, means for withdrawing the receiving means from receiving position while the button is thus clamped, buttonhole fly engaging means, mechanism for effecting relative movement 115 of said clamping means and buttonhole fly engaging means to perform a buttoning operation, and means for relieving the clamping pressure on the button before the buttoning operation is completed. 120

53. A buttoning machine having, in combination, button receiving means, means for clamping a button in said receiving means by pressure applied on the head and under the eye of the button, buttonhole fly engaging means, mechanism for operating said buttonhole fly engaging means to force the material adjacent to a buttonhole partially 125

- over the head of the button while the button is in the receiving means, means for withdrawing said receiving means from receiving position, means for relieving the pressure of the clamping means on the button after said receiving means is withdrawn, and means for causing the buttonhole fly engaging means to complete the buttoning operation after said pressure is relieved.
- 10 54. A buttoning machine having, in combination, button receiving means arranged to receive a button attached to a button piece when the work is initially presented to the machine, means for engaging a buttonhole fly at opposite sides of a buttonhole, mechanism for operating said buttonhole fly engaging means to position said means at the opposite sides of the head of the button while the button is in said receiving means
- 15 to assist in holding the button upright, means for withdrawing the receiving means from the button while the buttonhole fly engaging means is thus positioned, and means for causing the buttonhole fly engaging means to complete the buttoning operation after said receiving means is withdrawn.
55. A buttoning machine having, in combination, a button support, a plunger for engaging the head of a button on said support to clamp the button, a holder in which said plunger is mounted with provision for relative movement between the plunger and the holder in directions lengthwise of the plunger, means for operating the plunger to cause it to apply clamping pressure to the button, means for performing a buttoning operation with respect to said button, and means for causing said plunger operating means to release the pressure on the button before the buttoning operation is completed.
56. A buttoning machine having, in combination a button support, a plunger for engaging the head of a button on said support to clamp the button, a holder in which said plunger is mounted with provision for relative movement between the plunger and the holder in directions lengthwise of the plunger, means for operating the plunger to cause it to apply clamping pressure to the button, buttonhole fly engaging means carried by said holder, means for moving the holder relatively to the plunger to cause said buttonhole fly engaging means partially to complete a buttoning operation while the button is clamped, means for causing the plunger operating means to relieve the pressure on the button, and means for operating the holder to complete the buttoning operation after said pressure is relieved.
57. A buttoning machine having, in combination, a button support, a plunger for engaging the head of a button on said support to clamp the button, a holder in which said plunger is mounted with provision for relative movement between the plunger and the holder in directions lengthwise of the plunger, means for operating the plunger to cause it to apply clamping pressure to the button, buttonhole fly engaging means carried by said holder, means for moving the holder relatively to the plunger to cause said buttonhole fly engaging means to complete the buttoning operation while the button is clamped, means for causing the plunger operating means to relieve the pressure on the button, and means for operating the holder to complete the buttoning operation after said pressure is relieved.
58. A buttoning machine having, in combination, a button support, a plunger for engaging the head of a button on said support to clamp the button, a holder in which said plunger is mounted with provision for relative movement between the plunger and the holder in directions lengthwise of the plunger, means at the outer end of the plunger for operating the plunger, means for moving the holder and the plunger operating means together to cause the plunger to apply clamping pressure to the button, buttoning means carried by the holder, means for moving the holder relatively to the plunger to cause said buttoning means partially to complete a buttoning operation while the button is clamped, means for moving the plunger operating means away from the end of the plunger to relieve the pressure on the button, and means for operating the holder to complete the buttoning operation after said pressure is relieved.
59. A buttoning machine having, in combination, a button support, a plunger for engaging the head of a button on said support to clamp the button, a holder in which said plunger is mounted with provision for relative movement between the plunger and the holder in directions lengthwise of the plunger, plunger operating means mounted for movement with said holder and arranged to be positioned at the outer end of the plunger, a spring connection between the plunger operating means and the holder tending to maintain the plunger yielding in a normal position relatively to the holder, buttoning means carried by the holder, means for moving the holder relatively to the plunger to perform a buttoning operation, and means for causing the plunger operating means to relieve the pressure on the button before the buttoning operation is completed.
60. In a buttoning machine, the combination with a button support, of a plunger for engaging the head of a button on said sup-

port, plunger operating means arranged to be positioned at the outer end of the plunger, and spring means connected to said plunger operating means to cause the plunger to 5 press yieldingly upon the button.

61. In a buttoning machine, the combination with a button support, of a plunger for engaging the head of a button on said support, a holder in which said plunger is 10 mounted with provision for relative movement of the plunger and the holder in directions lengthwise of the plunger, means for moving the holder to carry the plunger into engagement with a button, plunger operating means mounted for movement with 15 the holder and arranged to be positioned at the outer end of the plunger, and a spring connection between the plunger operating means and the holder for determining a 20 normal position of the plunger relatively to the holder.

62. In a buttoning machine, the combination with a button support, of a plunger for engaging the head of a button on said support, plunger operating means arranged 25 to be positioned over the outer end of the plunger, and a yieldable bearing member between said operating means and the plunger.

63. In a buttoning machine, the combination with means for supporting a plurality of buttons, of plungers for engaging the heads of the buttons, and unitary means arranged to extend over the ends of said 30 plungers for operating the plungers.

64. In a buttoning machine, the combination with means for supporting a plurality of buttons, of plungers for engaging the heads of the buttons, a member arranged to 40 extend over the ends of said plungers, and spring means for operating said member to cause the plungers to press yieldingly on the buttons.

65. In a buttoning machine, the combination with means for supporting a plurality of buttons, of plungers for engaging the heads of said buttons, a member for operating 45 said plungers in unison, and mechanism for operating said member to relieve the pressure on the buttons before the buttoning operation is completed.

66. In a buttoning machine, the combination with means for supporting a plurality of buttons, of plungers for engaging the 55 heads of said buttons, a member arranged to extend over the ends of said plungers, spring means connected to said member to cause the plungers to press yieldingly on the buttons, and means for operating said 60 member to relieve the pressure on the buttons.

67. In a buttoning machine, the combination with means for supporting a plurality of buttons, of plungers for engaging the 65 heads of said buttons, means arranged to

extend over the ends of said plungers to hold them in engagement with the buttons and a yieldable bearing member between said holding means and each of said plungers.

68. In a buttoning machine, the combination with means for supporting a plurality of buttons, of plungers for engaging the heads of said buttons, a member arranged to extend over the ends of said plungers to 70 hold them in engagement with the buttons, and a spring held pin forming a yielding connection between said member and each plunger.

69. A buttoning machine having, in combination, means for supporting a plurality of buttons, plungers for engaging the heads of said buttons, a support for said plungers, a member carried by said support and arranged to extend over the ends of the plungers, means for moving said support and member to cause the plungers to press upon the buttons, means for performing buttoning operations with respect to said buttons, and means for moving said member relatively to the support to relieve the pressure of the plungers on the buttons before the buttoning operations are completed.

70. In a buttoning machine, a button positioning member having an opening therein to receive a button, and means for forcing the material adjacent to a buttonhole over the head of a button while the button is positioned in said opening, said member having an upstanding projection adjacent to its opening to raise the head of the button above portions of the member which extend beyond the sides of the button head.

71. In a buttoning machine, a button support having an opening therein to receive a button, buttonhole fly engaging members, and mechanism for relatively moving said support and members to cause the members to force the buttonhole fly over the head of a button on said support and to assume positions substantially at the sides of the button head, said support having an upstanding projection adjacent to its opening to raise the head of the button above portions of the support which extend beyond the sides of the button head.

72. In a buttoning machine, a button positioning fork having a relatively narrow upstanding button engaging portion extending along its button receiving opening.

73. In a buttoning machine, a button receiving fork 2 having an upstanding projection 200 thereon for positioning a button.

74. In a buttoning machine, button positioning means having an opening to receive a button, means for retaining the button in said opening, and mechanism for operating said retaining means to facilitate the release of the button.

75. In a buttoning machine, button posi-

tioning means having an opening to receive a button, yielding means for retaining the button in said opening, and means for varying the tension of said yielding means in time relation to the operative movements of the machine to facilitate the release of the button.

76. In a buttoning machine, button positioning means having an opening to receive a button, means for retaining the button in said opening, means for performing a buttoning operation with respect to the button, means for withdrawing said positioning means from the button, and mechanism for operating said retaining means to facilitate the release of the button.

77. In a buttoning machine, a button positioning fork, a member for retaining a button in said fork, a spring for holding said member in retaining position, and means operated in time relation to the operative movements of the machine for varying the tension of said spring.

78. In a buttoning machine, a button positioning fork, a member for retaining a button in said fork, a spring for holding said member in retaining position, means for performing a buttoning operation with respect to the button, means for withdrawing the fork from the button, and means operated in time relation to the operative movements of the machine for decreasing the tension of said spring to facilitate the release of the button.

79. In a buttoning machine, a button positioning fork, a member for retaining a button in said fork, a spring for holding said member in retaining position, means for subjecting said spring to a relatively increased tension when the parts of the machine are in work receiving position, and means for decreasing the tension of said spring after the machine is started.

80. In a buttoning machine, the combination with means for performing a buttoning operation, of means for discharging the work from the machine by engagement with the button head after the buttoning operation is performed.

81. In a buttoning machine, buttoning means arranged to extend over opposite sides of the head of a button and under the head to dispose the material of the button-hole fly in buttoned position, and means for engaging the button in said buttoning means and forcing the button out of said means after the buttoning operation is performed.

82. In a buttoning machine, a member for engaging the top of the head of a button, means operative at the opposite sides of the button to dispose the material adjacent to a buttonhole in buttoned relation to the button, and means for rendering said member operative to discharge the work from the

machine after the buttoning operation is performed.

83. A buttoning machine having, in combination, a plunger for engaging the top of the head of a button, means for causing said plunger to apply pressure to the button head to position the button, buttoning means arranged to dispose the material adjacent to a buttonhole in buttoned relation to the button, means for relieving the pressure of the plunger on the button head before the buttoning operation is completed, and means for rendering said plunger effective to force the button out of said buttoning means after the buttoning operation.

84. A buttoning machine having, in combination, a plunger for engaging the top of the head of a button, operating means for holding said plunger upon the button, buttoning means, mechanism for operating said buttoning means to force the material adjacent to a buttonhole over the head of the button, means for withdrawing said plunger operating means from the plunger before the buttoning operation is completed, and means for rendering said plunger operating means effective after the buttoning operation to force the button out of the buttoning means.

85. A buttoning machine having, in combination, a plunger for engaging the top of the head of a button, an operating member extending over the outer end of the plunger for holding the plunger upon the button, buttoning means arranged to extend over opposite sides of the button head to dispose the material adjacent to a buttonhole in buttoned relation to the button, means for withdrawing said operating member from the plunger before the buttoning operation is completed, and means for rendering said member effective to cause the plunger to force the button out of the buttoning means after the buttoning operation.

86. A buttoning machine having, in combination, a plunger for engaging the head of a button, a holder in which said plunger is mounted with provision for relative movement of the plunger and the holder in directions lengthwise of the plunger, a member arranged to extend over the outer end of the plunger to hold the plunger on the button, buttoning means on the holder, mechanism for moving the holder relatively to the plunger to cause said buttoning means to force the material adjacent to a buttonhole over the head of the button, means for moving said member away from the end of the plunger, means for limiting said movement of the member, and means for moving the holder in a direction to cause the plunger to be operated by said member to force the button out of the buttoning means.

87. In a machine of the class described, a plurality of operating instrumentalities for

performing operations in spaced locations on a piece of work, and power operated means for increasing or decreasing the spaces between the operative locations of 5 said instrumentalities.

88. In a machine of the class described, a plurality of operating instrumentalities for performing operations in spaced locations on a piece of work, and power operated means 10 comprising a friction clutch for varying the spacing of said instrumentalities.

89. In a machine of the class described, a plurality of operating instrumentalities for performing operations in spaced locations 15 on a piece of work, power operated means comprising a friction clutch for increasing or decreasing the spaces between the operative locations of said instrumentalities, and manual means for controlling the operation 20 of said clutch.

90. In a machine of the class described, a plurality of operating instrumentalities for performing operations in spaced locations on a piece of work, an operating member connected to said instrumentalities for adjusting 25 them in differently spaced relations, oppositely driven power elements, a member manually movable into position to be driven by either of said elements, and a connection between 30 said driven member and said operating member for adjusting said instrumentalities.

91. In a machine of the class described, a plurality of operating instrumentalities for 35 performing operations in spaced locations on a piece of work, an operating member connected to said instrumentalities for adjusting them in differently spaced relations, manually controlled power driven means for 40 operating said member, and means for limiting the operative movement of said member.

92. In a machine of the class described, a plurality of operating instrumentalities for performing operations in spaced locations on 45 a piece of work, an operating member connected to said instrumentalities for adjusting them in differently spaced relations, a rotatable crank member to which said oper-

ating member is connected, power driven means for operating said crank member to 50 adjust said instrumentalities, and means for limiting the movement of said crank member to substantially a half revolution.

93. In a machine of the class described, a plurality of operating instrumentalities for 55 performing operations in spaced locations on a piece of work, an operating member connected to said instrumentalities for adjusting them in differently spaced relations, a rotatable crank member to which said 60 operating member is connected, power means comprising a friction clutch for operating said crank member, and means for limiting the operative movement of said crank member.

94. In a buttoning machine, a plurality of sets of coöperating instrumentalities for performing buttoning operations with respect to a plurality of buttons, said sets of instrumentalities being adjustable to conform 70 to differences in spacing of the buttons, and power driven means for adjusting said sets.

95. In a buttoning machine, a plurality of sets of coöperating instrumentalities for performing buttoning operations with respect to a plurality of buttons, said sets of instrumentalities being adjustable to conform 75 to differences in spacing of the buttons, and power driven means comprising a manually 80 controlled friction clutch for adjusting said sets.

96. In a buttoning machine, a plurality of sets of coöperating instrumentalities for performing buttoning operations with respect 85 to a plurality of buttons, said sets of instrumentalities being adjustable to conform to differences in spacing of the buttons, power driven means for adjusting said sets to increase or decrease the spaces between them, 90 and treadle means for controlling the operation of said power driven means.

In testimony whereof I have signed my name to this specification.

HERBERT E. ENSLIN.
